UNITED STATES PATENT OFFICE.

OSCAR B. JOHNSON, OF INDIANAPOLIS, INDIANA.

HINGE FOR WINDOWS.

1,384,836.

Specification of Letters Patent. Patented July 19, 1921.

Application filed August 4, 1919. Serial No. 315,335.

To all whom it may concern:

Be it known that I, OSCAR B. JOHNSON, a citizen of the United States, residing at Indianapolis, in the county of Marion and State of Indiana, have invented certain new and useful Improvements in Hinges for Windows, of which the following is a specification.

This invention relates to window constructions more especially to windows mounted on hinges and which open inwardly, commonly known as "French windows." These windows have a great disadvantage in that rainstorms beating upon them cause water to creep in through the sill of the frame wetting the interior walls of the building. It is among the objects of this invention to obviate such disadvantages by the provision of means preventing the entrance of water while allowing the window to be swung inwardly whenever desired.

In carrying the objects of my invention into effect I provide a suitable member, as a bar, fixed to or integral with the exterior lower portion of the sash and extending downwardly so as to shed rain. I also provide means comprising a special hinge construction whereby the sash may be raised so that the downwardly extending lip or bar may be disengaged from the window sill and the sash swung inwardly. My invention includes a tension arrangement for partly releasing the lower hinge device from the weight of the sash.

Referring to the accompanying drawing forming a part hereof and in which similar reference characters denote similar parts, Figure 1 illustrates a side view of a window frame and sash embodying my invention, some parts being broken away for clearness.

Fig. 2 is a side elevation of the lower hinge structure with the window sash in lowered position.

Fig. 3 is a similar view with the sash raised.

Fig. 4 is a top plan view of the lower hinge structure.

Fig. 5 is a similar view with the sash partially opened.

Fig. 6 is an edge elevation of the lower hinge structure, and

Fig. 7 is a top plan view of the upper hinge structure.

The window frame 1 has an interior projection 2 extending upwardly from the sill 3 so as to provide an interior ridge on the

lower edge of the window. A window sash 4 having a downwardly extending lip 5 adapted to overlap the upwardly extending portion 2 is provided with hinges 6 and 7, 60 legs 8 and 9 respectively, of which are fixed to the window frame. Members 10 and 11 are mounted on the window sash and cooperate with members 12 and 13 respectively, forming part of the hinges 6 and 7. 65 A pivot member 15 is placed transversely of member 13 and fixed thereto; a similar transverse pivot 16 is fixed to member 11 and both pivots are connected by a lever 14. A pin 17 also pivoted to member 13 carries 70 a downwardly extending sector shaped member 18 formed approximately concentric to pivot 15, the sector having a plurality of notches 19 therein adapted to engage successively a pin 20 fixed on the inner side of 75 lever 14. A spring 21 is fastened to member 18 by pin 22 and extends in parallel relation to the sector portion of said member and is adapted to hold pin 20 in the notches in its various positions. The upper hinged 80 member has formed therein pivots 15' and 16' similar to 15 and 16 which are connected by link 23. The member 12 carries a roller 25 and a spring 26 is coiled around 16' and roller 25 as shown, and the end of 85 the spring is fixed to pin 27. A plurality of such devices may be used if desired.

In its closed position the window and hinges are in the position shown in full lines in the drawing. When it is desired to open 90 the window, lever 14 is pressed downwardly disengaging the pin 20 from the upper notch in sector shaped member 18. In the downward movement of the lever the sash is raised by the lever between pivots 15 and 16 95 so that lip 5 is disengaged from projection 2. The lever 14 is now in its lower position as shown in dotted lines with pin 20 engaging the lower notch 19 and locked thereby. The window frame has a portion 28 cut out 100 from the upper end thereof in order that when the lever 14 is pressed downwardly to raise the sash, sufficient clearance may be provided so as to allow the sash to be freely lifted to disengage the lip 5 from the projection 2. The spring member 26 located on the upper hinge is wound in such a way that it tends to lift the window sash and thereby relieves the mechanism of the lower hinge from undue strain caused by the weight of 110 the sash.

Having thus fully described my said in-

vention, what I claim as new and desire to secure by Letters Patent, is:

1. In a hinge construction a movable structure, a stationary structure, a leg fastened to one of said structures and carrying a hinge, a member fastened to the other structure, and lever means interposed between said hinge and member adapted to raise said member and said movable structure without separating the leaves of the hinge.

2. In a hinge construction a leg adapted to be fastened to a window frame and carrying a hinge pivot, a member adapted to be fastened to a sash, and lever means interposed between said pivot and member adapted to raise said member without separating the leaves of the hinge.

3. In a hinge construction a leg adapted to be fastened to a window frame and carrying a hinge pivot, a member adapted to be fastened to a sash, and a lever pivoted to a portion of said hinge and to said member adapted to raise said member without separating the leaves of the hinge.

4. In a hinge construction a leg adapted to be fastened to a window frame and carrying a hinge pivot, a member adapted to be fastened to a sash, a lever pivoted to a portion of said hinge and to said member adapted to raise said member, and spring pressed stop means for holding said member in raised and lowered positions.

5. In a hinge construction a member adapted to be fastened to a sash and having a pivot fixed thereto and transversely thereof, a hinge, a member mounted on said hinge and also having a pivot fixed thereto and transversely thereof, and a lever mounted on said pivots extending rearwardly thereof.

6. In a hinge construction, a member

adapted to be fastened to a sash and having a pivot fixed thereto and transversely thereof, a hinge, a member mounted on said hinge and having a pivot fixed thereto and transversely thereof, a lever mounted on said pivots extending rearwardly thereof, a pin on the rear portion of said lever, and means for yieldingly engaging said pin to lock said lever in raised and lowered positions.

7. In a hinge construction a locking device comprising a sector shaped member pivotally mounted on a hinged member carrying a lever having a pin contacting with said sector shaped member, spring means fixed to said sector shaped member acting on said pin and recesses in said member for receiving said pin.

8. In a hinge construction a leg adapted to be fastened to a window frame and carrying a hinge pivot, a member adapted to be fastened to a sash, transverse pivots on said member and hinge connected by a link, and a spring member fastened to one of said pivots and to said hinge to provide the tension aiding in lifting said sash.

9. In a hinge construction a leg adapted to be fastened to a window frame and carrying a hinge pivot, a member adapted to be fastened to a sash, transverse pivots on said member and hinge connected by a link, and a spring fastened to one of said pivots and coiled about a roller the end of said spring being fixed to said hinge.

In witness whereof, I have hereunto set my hand and seal at Indianapolis, Indiana, this 18th day of July, A. D. nineteen hundred and nineteen.

OSCAR B. JOHNSON. [L. s.]
